(57) **CLAIM**

The ornamental design for a coffee tamper set, as shown and described.

DESCRIPTION

FIG. 1 is a top, front and right side perspective view of a coffee tamper set showing my design;

FIG. 2 is a bottom, rear and right side perspective view is a rear perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 depicts an enlarged detail view of portion 9 shown in FIG. 1; and,

FIG. 10 is a perspective reference view showing the design with two parts in a combined state.

The broken lines in the drawings depict portions of the coffee tamper set that form no part of the claimed design. The short dash-long dash broken lines in FIGS. 1 and 9 designating the boundary of the enlarged view, form no part of the claimed design.

1 Claim, 10 Drawing Sheets
